J. S. COX,
PORTABLE TRACK FOR HAY CARRIERS OR THE LIKE,
APPLICATION FILED OCT. 18, 1915.

1,177,932.

Patented Apr. 4, 1916.

Inventor.

UNITED STATES PATENT OFFICE.

JOHN S. COX, OF HOLTVILLE, CALIFORNIA.

PORTABLE TRACK FOR HAY-CARRIERS OR THE LIKE.

1,177,932.

Specification of Letters Patent.

Patented Apr. 4, 1916.

Application filed October 18, 1915. Serial No. 56,627.

To all whom it may concern:

Be it known that I, JOHN S. COX, a citizen of the United States, residing at Holtville, in the county of Imperial and State of California, have invented new and useful Improvements in Portable Tracks for Hay-Carriers or the like, of which the following is a specification.

My invention relates to an apparatus for stacking hay, grain, and the like, in which the hay-unloading device is suspended from a trolley whereby the hay is removed from a wagon and moved along the trolley support and deposited on the stack.

15 My invention relates in particular to an apparatus in which two uprights connected by a cable support a trolley from which the hay-loading and unloading device is suspended. The uprights are pivoted at 20 their lower ends and are provided with means for simultaneously moving the trolley cable so that the same may be swung in either direction to occupy a position approximately parallel to its normal position.

25 It is an object of this invention to provide means simple in construction and positive in operation whereby the cable supports may be easily and quickly swung on their pivots in their adjusted position and 30 firmly locked therein.

Other objects of the invention will appear as the description proceeds.

35 My invention consists in the combination and arrangement of parts hereinafter described and claimed.

In the accompanying drawings which form a part of this specification, I have illustrated a convenient and practical embodiment of my invention, and in which: 40 Figure 1 is a perspective view of my apparatus. Fig. 2 is an end view thereof looking from the left of Fig. 1. Fig. 3 is a detail view showing the windlasses upon which the cables operating the apparatus 45 are wound. Fig. 4 is a front elevation of the apparatus showing the hay-stacker in operation.

11 and 10 designate a pair of vertical supports or uprights, referred to herein- 50 after as first and second uprights, re- spectively, between whose upper ends a trolley cable or rope 12 is secured. The lower end of each of said uprights is positioned in a metal shoe 13 consisting of 55 a base plate 14 suitably secured by means of spikes 15—15 and having a pair of spaced

vertical lugs 16—16 adapted to receive the lower end of the upright. The lugs 16—16 are provided with apertures 17—17 for the reception of a pivot pin 18 passing through the lower end of the upright, whereby the upright may be swung in either direction in a plane at right angles to the trolley cable 12. Guy ropes 19—19 are connected to the tops of the uprights and lead therefrom obliquely downward to the ground. The upright 10 is more subject to a twisting movement than upright 11 and for this reason the upper end of the guy rope 19 connected thereto is fastened at its upper end to the transverse member of a U-shaped link 20' which is pivoted to oppositely disposed lateral faces of the upper end of the upright 10. The lower ends of the guy ropes are securely fastened to stakes 20—20 which are located in a straight line passing through the lower ends of the uprights 10 and 11. It is obvious from this construction that the uprights may be swung either to the right or left, the distance from the top of the upright 10 to the stake 20 remaining the same. The following means are provided for effecting the pivotal movement of the uprights: A cable or rope *a* is fastened to the top of the first upright 11 and thence leads at an angle 70 to the ground and over a pulley 21 suitably fastened to a stake 22 in front of said upright, thence horizontally on the ground to a pulley 23 fastened to a suitable stake 24 in the rear of said upright. Thence the cable passes in a direction parallel to the trolley cable to and over a pulley 25 fastened to a stake 26 in the rear of the second upright 10 thence to the top of the latter where it is fastened. A cable *b* is 75 fastened to the top of the first upright 11 and leads over a pulley 41, secured to the stake 24, thence to and over a pulley 42 fastened to the stake 26, thence to a winding drum 27 located in an aperture 28 in the upright 10. The shaft 27' of said drum is suitably journaled in lugs 29—29' extending from a pair of lateral plates 37—37 secured to the sides of the upright 10, and is 80 provided with a crank handle 29 and a pawl 30 which engages the ratchet teeth 30' on said drum. The cable *b* thence passes to and over a pulley 31, thence to the top of the upright 10 to which it is secured. The pulley 31 is movable, and is connected to a 85 cable *c* passing over a small pulley 32 which is secured to a suitable stake 33 in

front of said upright 10. The cable d passes over pulley 32 to an auxiliary winding drum 34 mounted on the side of the upright 10. The shaft is suitably journaled in lugs 36—36 5 extending from the plates 37—37. The shaft is operated by means of a crank handle 38. A pawl 39 engages ratchet teeth 40 at one end of the drum. It should be noted that the stakes 22 and 24 to which pulleys 21 10 and 23, 41, respectively, are secured and are positioned in the plane in which the first upright 11 swings in its pivotal movement. The stakes 28 and 26 to which pulleys 32 and 25, 42, respectively, are secured, 15 are positioned in the plane in which the second upright 10 swings in its pivotal movement. I have selected the length of the horizontal section of cable extending on either side from the foot of the upright and 20 the length of the two inclined sections leading to the top of the upright so as to form a right-angled triangle whose lateral sides are of equal length; the right angle being at the apex. However, it is not necessary 25 that the respective cable lengths be proportioned to form a right-angled triangle as described. However, it is essential that the cable sections constituting the lateral sides of the triangle be positioned in the plane 30 of the pivotal movement of the upright, so that any pull exerted thereon in either section, will be in the same plane.

Operation: From the foregoing description, the operation of the apparatus will be 35 easily understood. Assuming that the trolley cable has been used in the position shown in Fig. 1 for building up the center of the hay-stack A, shown in Fig. 4, and it is desired to stack hay on the other side—that is, 40 toward the left, looking from the end shown in Fig. 2—the main winding drum 27 is rotated by means of the handle 29 in a contrary clock-wise direction causing the cable b to pass in a direction from the top of the 45 upright 11 over pulleys 41, 42 and 31 to the top of the upright 10. The uprights will swing toward the left and occupy the position shown in dotted lines in Fig. 1. When the uprights occupy this position, or any 50 other position except the vertical upright one shown in full lines in Fig. 1, there will be more or less slack in the cables a and b , proportionate to the degree of declination of the uprights from the perpendicular. 55 The reason for this slackness in the cables a and b will be easily understood from a study of Fig. 2. It is obvious that when the upright is in its vertical position the sum of the cable sections between the pulley 60 31 and the top of the upright 10 which form the lateral sides of the right-angled triangle above referred to (and which are designated as a' and b' , respectively—see Fig. 2) is greater than the sum of said cable lengths 65 when the upright is in its inclined position,

as shown in dotted lines in Fig. 2. It is not necessary to prove this proposition as it is well known that the sum of the sides of a right-angled triangle has a maximum value when a perpendicular, dropped from 70 said right angle to the hypotenuse, meets the middle point thereof. This condition is fulfilled when the uprights are in their vertical position. Any other position of the uprights will cause the sum of the sides a' and b' to be less. Means must therefore be provided for taking up the slack in the cables a and b so that the uprights will be firmly held in adjusted position as they are 75 swung on their pivots. The means referred to is the auxiliary drum 34 upon which the cable d is wound. By winding up the cable d on drum 34, the pulley 31 is moved toward the pulley 32 thereby increasing the 80 length of the side a' and also the distance between the pulleys 31 and 42. The upright 10 will be swung upward toward the vertical position to a slight degree to take up the slack in the cable a which is due to the changed shape of the cable triangle 85 about the upright 11 for the reasons explained in connection with the cable triangle formed about the upright 10. 90

For the reasons above explained, the sum of the sides of the right-angled triangle in 95 which the upright 11 is located, will be less when the upright 11 occupies the inclined position indicated by dotted lines in Fig. 1. Therefore the upright 10 will be inclined from the perpendicular at a smaller angle 100 than the support 11. For all practical purposes, however, this difference in inclination is immaterial and does not affect the operation or utility of the apparatus in the least. After the hay-stack has been built up vertically below the trolley line, indicated by 105 dotted lines in Fig. 1, the supports may be inclined still more toward the left by operating the drums 27 and 34 as just described. If it is desired to build up the stack on the 110 right side thereof, the uprights will be swung in that direction as will be understood.

While I have shown the preferred form 115 of my apparatus as now known to me, it will be understood that I do not confine myself to the specific construction and arrangement as described.

Various changes will suggest themselves to those skilled in the art without departing 120 from the spirit of my invention as claimed.

I claim:

1. In a portable track for hay carriers or the like, the combination of a first upright and a second upright spaced from each other and pivoted at their lower ends, a trolley cable connecting their upper ends, guy ropes leading from the upper ends of said uprights to points constituting the ends of a straight line passing through the pivots of 125 130

- said uprights whereby the same may be swung on their pivots in planes at right angles to said trolley cable, a main winding drum, an auxiliary winding drum, said drums being mounted on said second upright, separate drum operating means, a cable having its ends secured to the top of said uprights and leading from the top of said first upright obliquely downward to a point in front thereof, thence in a horizontal direction to a point in the rear thereof, thence horizontally to a point in the rear of the second upright, thence obliquely to the top thereof, a second cable having its ends secured to the tops of said upright, leading from the top of said first upright obliquely downward to a point in the rear thereof, thence horizontally to a point in the rear of said second upright, thence around said main winding drum, thence over a movable pulley, thence obliquely upward to the top of said second upright, and a third cable operatively connected to said auxiliary drum leading to a point in front of said second upright and secured to said movable pulley, all of said points around which said cables pass being located approximately in the planes of the pivotal movement of said uprights.
2. In a portable track for hay carriers or the like, the combination of a first upright and a second upright spaced from each other and pivoted at their lower ends, a trolley cable connecting their upper ends, means for limiting the pivotal movement of said uprights in a plane at right angles to said trolley cable, a main winding drum, an auxiliary winding drum, separate drum operating means, a cable having its ends secured to the tops of the said uprights and leading from said first upright obliquely downward to a point in front thereof, thence in a horizontal direction to a point in the rear thereof, thence in a horizontal direction to a point in the rear of the second upright, thence to the top thereof, a second cable having its ends secured to the tops of said uprights and leading from said first upright obliquely downward to a point in the rear thereof, thence horizontally to a point in the rear of said second upright, thence around said main winding drum, thence over a movable pulley, thence obliquely upward to the top of said first upright, and a third cable operatively connected to said auxiliary drum leading to a point in front of said second upright and secured to said movable pulley, all of said points around which said cables pass being located approximately in the planes of the pivotal movement of said uprights.
3. In a portable track for hay carriers or the like, the combination of a first upright and a second upright spaced from each other, a trolley cable connecting their upper
- ends, said uprights being pivoted at their lower ends for movement in a plane at right angles to said trolley cable, a main winding drum, an auxiliary winding drum, means for operating said drums, a flexible connection having its ends secured to the tops of said uprights and leading to a point in front thereof, thence to a point in the rear thereof, thence to a point in the rear of said second upright, thence to the top thereof, a second connection being secured to the tops of said uprights and leading to a point in the rear thereof, thence to a point in the rear of said second upright, thence around said main winding drum, thence over a movable pulley, thence to the top of said second upright, and a third flexible connection operatively connected to said auxiliary drum leading to a point in front of said second upright and secured to said movable pulley, all of said points around which said connections pass being located approximately in the planes of the pivotal movement of said uprights.
4. In a portable track for hay carriers or the like, the combination of a first upright and a second upright spaced from each other, a trolley cable connecting their upper ends, all of said uprights being pivoted at their lower ends to swing in a plane at right angles to said trolley cable, a flexible connection leading from the top of said first upright to a point in front thereof, thence to a point in the rear thereof, thence to a point in the rear of the second upright, thence to the top thereof, a second flexible connection leading from the top of the first upright to a point in the rear thereof, thence to a point in the rear of the second upright, thence over a movable pulley, thence to the top of said second upright, means interposed in the path of said second connection for moving the latter in either direction and locking the same, and a third flexible connection leading to a point in front of said second upright and secured to said movable pulley, means for moving said third connection in either direction and locking the same in position, all of said points around which said flexible connections pass being located approximately in the planes of the pivotal movement of said uprights.
5. In a portable track for hay carriers or the like, the combination of a first upright and a second upright spaced from each other, a trolley support connecting their upper ends, each of said uprights being pivoted at its lower end to swing in a plane at right angles to said trolley support, a flexible connection leading from the upper part of the first upright to a point in front thereof, thence to a point in the rear of said second upright, thence to the upper part thereof, a second flexible connection leading from the upper part of said first

upright to a point in the rear thereof, thence to a movable pulley in front of said second upright, thence to the upper part of said second upright, means for moving said second connection in either direction of its path, a third flexible connection leading to said movable pulley, all of said points around which said connections pass being located approximately in the planes of the pivotal movement of said uprights, and means for moving said third flexible connection in either direction of its path.

6. In a portable track for hay carriers or the like, the combination of a first and a second upright, a trolley track connected to their upper ends, said uprights being pivoted to swing in planes transversely to said track, a flexible connection having its ends secured to the upper ends of said uprights, a second flexible connection having its ends secured to the upper ends of said uprights, means for moving said connections for swinging said uprights on their pivots, and means for taking up the slack in said connection.

7. In a portable track for hay carriers or the like, the combination of a first upright and a second upright spaced from each

other, a trolley track connecting their upper ends, each of said uprights being pivoted at its lower end to swing in a plane at right angles to said trolley track, a flexible connection having its end secured to the upper ends of said uprights, a second flexible connection having its ends secured to the upper ends of said uprights, means for moving said second connection in either direction of its path, a third flexible connection for taking up the slack in said two first named connections, and means for moving said third connection in either direction of its path.

8. In a portable track for hay carriers or the like, the combination of a first and second upright, a trolley track connected to their upper ends, said uprights being pivoted to swing in planes transversely to said track, a flexible connection having its ends secured to the upper ends of said uprights, a second flexible connection having its ends secured to the upper ends of said uprights and means operatively connected to one of said connections for swinging said uprights on their pivots in the same direction.

In testimony whereof I have signed my name to this specification.

JOHN S. COX.
